AUTOMOBILE WATER HEATER

Filed Oct. 29, 1928

UNITED STATES PATENT OFFICE

WALTER PRUSACKI, OF ST. LOUIS, MISSOURI

AUTOMOBILE WATER HEATER

Application filed October 29, 1928. Serial No. 315,656.

This invention relates to certain new and useful improvements in automobile water heaters, the peculiarities of which will be hereinafter fully described and claimed.

5 The main objects of my invention are to provide means for keeping the water in the engine and radiator of an automobile or other machine, from cooling below operative temperature during a stop in cold weather, or 10 when in a garage subject to low temperature; secondly, means to cause a circulating stream of heated water under such circumstances through a circulating pipe that ordinarily conducts the cooling water; and thirdly, relating to other features herein described 15 and claimed.

In the accompanying drawing in which like reference numerals indicate corresponding parts,

20 The single figure represents an engine block with my improvements applied thereto, partly in section and partly in perspective.

Referring to the drawing, the numeral 1 25 designates the engine block of an automobile or other machine having an internal combustion engine with a water jacket and connected radiator for cooling the water circulated therethrough while running.

My circulating pipe is attached as usual to 30 the engine block by a coupling head 2, and rubber hose connection at the discharge end 3 to the radiator (indicated). Intermediate of the ends of this pipe, I provide a water-heating chamber, preferably by an enlargement 4 like an elbow in said pipe, and preferably having a removable cover 5 to which is secured a pot 6 containing an electric heating coil on a frame 7—or otherwise adapted to 35 heat the water in the adjacent portion of said pipe.

This coil is suitably wired to a source of 40 electricity and controlled by a switch button 8, so as to heat said pot when desired, and thus the water flowing around it.

45 In the ordinary use of the circulating water while the engine is running, the flow is effected by the usual pump. When the engine is not running, I have provided means to cause the water to circulate,—preferably a 50 fan pump having blades 9 mounted inside

said chamber near the exit passage 10, on a shaft 11 passing through a stuffing-box bearing 12, to a small auxiliary motor 13, suitably wired to a source of electricity, and controlled by a switch button 14 on the dash 55 board of the automobile, or elsewhere.

The fan blades when not operating, allow the water to flow through said chamber under the impulse of the usual pump when the engine is running, and the circulating water 60 system is used for cooling the engine block in the usual manner.

When the engine is stopped in cold weather and the engine is not running, I start the auxiliary motor by operating the button 14, and the heating coil by the button 8, so as to establish a flow of heated water through my chambered circulating pipe—and thus avoid chilling the engine, or freezing the water,—and facilitate starting again. The buttons are 70 operated to cut out the heating coil and motor on starting the engine again.

An independent battery 15 is preferably 75 used for the motor and heater, and one wire 17 leads from the battery through a switch 16 to the button 8, and the other wire 18 to the other side of the same button, which is thence connected by wires 19 and 20 to the heater coil through a current indicator 21, or otherwise. 80

A double-contact terminal 22 is provided for cable plug connection,—one contact located in the wire 17, and the other in the wire 18. These contacts are connected to the button 14 by wires 23 and 24 respectively, and thence through the indicator—or otherwise—to the auxiliary motor by wires 25 85 and 26.

The switch 16 is a safety switch and is preferably hidden to lessen the liability of being tampered with. It controls both buttons and must be thrown to contact position before the buttons 8 and 14 can energize the heater and motor respectively from the battery. It 90 should be opened for safety as indicated when buttons 8 and 14 shut off the heater and auxiliary motor; also when a cable plug is adjusted to connect said terminal 22 with an electric circuit in a garage when it is desired 95 100

to keep the circulating water heated in cold weather.

This terminal can also be used with the battery for cable connection to a lamp in looking up trouble, or making repairs at night out on the road.

Thus my form of circulating pipe is adapted to be used in the usual way for the water-cooling system of the engine, yet can be readily adapted to circulate heated water through the system in cold weather during stops outside, or in a garage.

I claim:

1. An automobile water heater comprising a circulating pipe connecting engine block and radiator having walls forming an enlargement chamber with stuffing-box bearing, a shaft mounted in said bearing, a fan pump on the inner end of said shaft within said chamber, an auxiliary motor electrically connected for said shaft, and a heating device for said chamber.

2. An automobile water heater for use when automobile is not running comprising a circulating pipe connecting engine block and radiator, an electric heating device for said pipe mounted intermediate of its ends, a pump for said circulating pipe, operative means for said pump when automobile is not running, a source of electricity, a terminal contact for said pump-operative means and heating device, a cable connection from said terminal contact to the source of electricity, controlling buttons and a switch hidden from view and controlling the current from the source of electricity to said heating device and pump-operative means, substantially as described.

3. An automobile water heater comprising a circulating pipe connecting engine block and radiator, an electric heating device mounted intermediate the ends of said pipe, a rotary fan pump located in the said pipe adjacent to the heating pipe and allowing the water to flow between its blades when not rotating and means to operate said pump and cause a flow of water when the automobile is at rest, substantially as described.

In testimony whereof I have affixed my signature.

WALTER PRUSACKI.
